UNITED STATES PATENT OFFICE.

PAUL ROUSSEY, OF BROOKLYN, NEW YORK.

SIGNAL DEVICE.

1,356,472.

Specification of Letters Patent. Patented Oct. 19, 1920.

Application filed March 12, 1920. Serial No. 365,316.

To all whom it may concern:

Be it known that I, PAUL ROUSSEY, a citizen of the United States, residing at Brooklyn, in the county of Kings and State 5 of New York, have invented new and useful Improvements in Signal Devices, of which the following is a specification.

This invention relates to signal devices. More particularly, it relates to that class of 10 signals which are used in conjunction with internal combustion engines. The device is to be used upon an automobile, which embodies the type of engine mentioned.

The principal object of the present invention is to produce a device which embodies a signal operatively connected with means that is responsive to the force of compression of an internal combustion engine, for not only moving the signal to be 20 exposed to view from its normal position of concealment, but to continuously move or reciprocate the signal within certain prescribed limits, while the signal is exposed to view.

With the above and other objects in view, the invention resides in the particular provision, combination and arrangement of parts more fully described in the following specification and illustrated in the accompanying drawings, in which:—

Figure 1, is a diagrammatic view illustrating the relative disposition of the principal parts of the invention.

Fig. 2, is an elevation illustrating a manner in which the signal may be normally concealed.

Fig. 3, is a plan view of the control valve and its connections.

Fig. 4, is a longitudinal sectional view 40 taken on the line 4—4 of Fig. 3.

Fig. 5 is a transverse sectional view taken on the line 5—5, of Fig. 4.

Fig. 6, is a rear elevation of the means which actuates the signal.

Fig. 7, is a central vertical sectional view 45 taken on the line 7—7 of Fig. 6.

Fig. 8, is a transverse sectional view taken on the line 8—8 of Fig. 7.

Fig. 9, is a diagrammatic view, illustrating the scheme of the invention, generally.

The device of the present invention consists generally of a signal; means including a cylinder having a piston operable therein which is connected to the signal— 55 the piston being responsive to the force of compression of an internal combustion en-

gine, in conjunction with which the device is used; a passage which extends from the engine cylinder to the first mentioned cylinder; a control valve in the said passage; which valve is operatively connected to the foot brake pedal; a device for overcoming the action of suction of the engine yet at the same time permitting the force of compression of the engine to have effect; and 65 means for effecting the reciprocation of the signal within certain prescribed limits, while the signal is exposed to view.

Referring now to the drawing, it will be seen, that the engine cylinder 10, is connected to the cylinder 11, forming a part of the means for effecting the actuation of the signal 12, by a passage X formed by divers devices to be hereinafter described, it being formed principally by a tube 13, made up 70 from suitable materials. The tube 13 has one end thereof connected to the engine cylinder by a bushing 14, which may be fitted into the opening left by the ordinary test valve in present use in connection with the 75 engine cylinder. These test valves are of standard make consequently the opening left by each when removed, is in all cases of one size regardless of the type of engine. The signal 12 is preferably arranged at the rear 80 of the vehicle, at some conspicuous location, and is normally concealed from view. In the present instance the signal 12 is concealed by the license plate P which usually carries means of attachment. The license plate in 85 fact, is in its nature a support, and has secured thereto a casing 15. The cylinder 11 is arranged within the casing 15. A piston 16 is arranged for movement within said cylinder 11. The piston 16 is provided 90 with a rod 17 and secured to the upper end thereof, which protrudes from the cylinder 11, is a bracket 18, and this bracket 18 carries the signal 12. A convolute spring 19 is interposed between the piston 16 and the 95 head 20 of the cylinder 11. The passage X between the cylinder 10 and the cylinder 11 is controlled by a valve 21, the plug 22 of which, is provided with an extension, which has formed therewith or otherwise 100 secured thereto a lever 23. The plug 22 is held by the normal tendency of a spring 24 in such a position as to be non-obstructive to the passage X. A flexible element 25 connects the lever 23 with the brake foot 105 pedal 26. The normal non-braking position of the pedal 26 is such as to constrain the

110

element 25 to hold the plug 22 in such a position as to obstruct the passage X. Upon movement of the pedal 26 to a braking position, it should be understood that, the 5 spring 24 will move the plug 22 to its non-obstructing position. The spring 24 functions immediately the pedal 26 is moved to but a small degree, consequently the signal will be brought to view as the vehicle is 10 merely being slowed and does not require that the pedal be pushed entirely to the limit of its inward braking movement before the signal will be exposed. The flexible element 25 or its equivalent may be used to al- 15 low extra movement of the foot pedal 26 subsequent to that which is sufficient to effect the exposition of the signal 12. The casing of the valve 21 is provided with a part 27 through which the pressure behind 20 the piston 16 finds egress to permit the signal 12 to lower to its position of concealment.

In order that the signal 12 may be made to move to a position of exposition; and in 25 order that the force of compression derived from within the engine upon the compression of the piston operating within the particular cylinder of the engine to which the device is connected; and in order that the 30 signal may not be completely moved downwardly to a position of concealment there is provided in the passage X a device 28, which includes a casing 29. Arranged internally of the casing 29, is a globular ele- 35 ment 30, which is adapted to permit the force of compression to pass to the cylinder 11, but which prevents the force of suction of the engine from affecting the piston 16. The casing 29 is provided with a transverse 40 wall having an opening therein, and a seat 31, which receives the element 30 on the suc- 45 tion stroke of the engine piston. A convolu- 50 tive spring 32 is interposed between the ele- 55 ment 30 and a by-pass member 33. This spring 32 is sufficiently strong to overcome the force of compression entering the pas- 60 sage X upon the explosion stroke of the engine piston, but is not strong enough to overcome the force of compression of the 65 compression stroke of the engine piston, consequently the signal is only affected by the compression brought to bear by the compression stroke of the engine piston.

In order that the signal may be continu- 55 ously moved up and down at the time it is exposed to view and within certain pre- 60 scribed limits, the wall of the cylinder 11 is provided with an aperture 34. This aper- 65 ture 34 is arranged in the wall of the cylinder 11 in such a position so that excess pres- 65 sure within the cylinder 11 which accumu- 70 lates by reason of the successive compression strokes of the engine piston, may find egress through said aperture 34, and when the pres- 75 sure within the cylinder falls below a pre-

determined degree, the piston 16, by reason of the spring 19, will be moved downwardly past the aperture 34, consequently the signal 12 will be moved downwardly. The signal remains in an intermediate position only 70 long enough to be raised again by the in- 75 crease of pressure within the cylinder 11 caused by the timely succeeding stroke of the engine piston. The reciprocation of the signal 12 continues until the plug 22 is 75 moved to the position shown in Fig. 4 of the drawing. Suitable springs S are employed for cushioning the action of the pressure upon the piston 16 in moving the signal 12 to view.

If desired provision may be made for illuminating the signal 12 at night. In the drawing there has been shown an arm 35 which is connected to the upper end of the piston rod 17. The arm 35 actuates a circuit 80 closer 36 arranged in a circuit with suitable batteries and a lamp 37. The lamp is dis- 85 posed in a position so as to readily illuminate the signal 12 when the lamp is lighted.

What is claimed as new is:—

1. In a device as characterized, a nor- 90 mally concealed signal, means responsive to the force of compression of an engine for effecting the exposition of said signal to view, and means for effecting reciprocation 95 of said signal while exposed to view.

2. In a device as characterized, a nor- 100 mally concealed signal, means responsive to the force of compression of an engine, said means including a spring valve having a lever, a foot brake pedal, a flexible element connecting said foot pedal and said valve lever, said valve being opened when the said pedal is moved for braking action, and said valve being closed when said pedal is in a 105 non-braking position, and means for effecting the reciprocation of said signal while exposed to view.

3. In a device as characterized, a nor- 110 mally concealed signal, means responsive to the force of compression of an engine in- 115 cluding a cylinder having a piston operable therein to which said signal is connected; a passage leading from the cylinder of the engine to said first cylinder, a device in the 120 passage for overcoming the suction action of the engine and for permitting the force of compression of the engine to have egress to said first cylinder to actuate said piston; and means for effecting the reciprocation of said signal while exposed to view.

4. In a device as characterized, a nor- 125 mally concealed signal, means responsive to the force of compression of an engine in- 130 cluding a cylinder having a piston operable therein to which said signal is connected; a passage leading from the cylinder of the engine to said first cylinder, a device in the passage for overcoming the suction action of the engine and for permitting the force 130

of compression of the engine to have egress to said first cylinder to actuate said piston; a vent in said first cylinder to expend a predetermined amount of pressure within 5 said first cylinder to permit the signal to lower a predetermined intermediate degree, said signal being raised upon each compression stroke of the engine piston a predetermined degree until said passage is 10 obstructive.

5. In a device as characterized for a motor driven vehicle, a normally concealed signal, pneumatic compression means for effecting the exposition of said signal to 15 view, and for reciprocating the signal while exposed, and a motor control part for effecting the operation of said pneumatic suction means.

6. In a device as characterized for a 20 motor driven vehicle, a normally concealed signal, pneumatic compression means for

effecting the exposition of said signal to view, and for reciprocating the signal while exposed, a motor control part for effecting the operation of said pneumatic suction 25 means, and a compensating operative connection between said pneumatic suction means and said motor control part.

7. In a device as characterized for a motor driven vehicle, a normally concealed 30 signal, means responsive to the force of compression of the motor of the vehicle for effecting the exposition of said signal to view and for retracting the signal while exposed, retractile springs forming a part of 35 said means for effecting the concealment of said signal, and a motor control part for effecting the operation of said means.

In testimony whereof I have affixed my signature.

PAUL ROUSSEY.
